UNITED STATES PATENT OFFICE.

HERBERT O. SHULTS, OF CHICAGO, ILLINOIS, ASSIGNOR TO E. L. MASURE COMPANY, OF CHICAGO, ILLINOIS, A CORPORATION OF ILLINOIS.

DESIGN FOR UPHOLSTERY BRAID.

Application filed July 9, 1928. Serial No. 27,429. Term of patent 7 years.

To all whom it may concern:

Be it known that I, HERBERT O. SHULTS, a citizen of the United States, residing at Chicago, Cook County, Illinois, have invented a new, original, and ornamental Design for Upholstery Braid, of which the following is a specification, reference being had to the accompanying drawing, forming part thereof, in which the single figure discloses a braid embodying my new design, the limits of a repeat unit of the design being designated by arrows.

I claim:

The ornamental design for upholstery braid as shown and described.

HERBERT O. SHULTS.
